ATTORNEY.

UNITED STATES PATENT OFFICE.

CAMERON McGREGOR SYKES, OF BIRMINGHAM, ENGLAND, ASSIGNOR TO W. & T. Avery, Limited, of BIRMINGHAM, ENGLAND.

POISE-WEIGHT OF STEELYARDS.

Application filed May 6, 1922. Serial No. 558,990.

To all whom it may concern:

Be it known that CAMERON McGREGOR SYKES, a subject of the King of Great Britain, residing at Soho Foundry, Birmingham, England, has invented a new and useful Improvement Connected with the Poise-Weights of Steelyards; and he does hereby declare the following to be a full, clear, and exact description of the same.

10 This invention has reference to improvements connected with the poise weights of steelyards and has for its object to improve the loading of the poise weight so as to alter the effective weight thereof in order to obtain the correct balance of the weighing apparatus or the like in connection with which it is employed, the invention residing more particularly in the location or disposition of the loading chamber and in the shape of 15 the compartments therein which receive and 20 the compartments therein which receive and contain the loading material.

The present invention comprises a poise weight for steelyards wherein the loading chamber of the poise weight is disposed 25 equally on either side of a vertical line passing through the fulcrum knife edge of the steelyard; the invention further resides in the construction of the loading chamber, more particularly in the shape of the compartments 30 therein and the means of attachment of the loading chamber to the poise weight.

The preferred means of carrying the present invention into effect will now be described in conjunction with the accompanying sheet of drawings which illustrate one embodiment thereof. In the drawings:—

Fig. 1 is a side elevation of the improved construction of poise weight mounted upon 40 a steelyard.

Fig. 2 is a perspective view of the loading chamber removed from the poise weight, and

Fig. 3 is a section taken on line 3—3 of 45 Fig. 1.

The present invention is applied to a poise weight 4 which is mounted upon a steelyard 5 and is provided with the ordinary runners or rollers 6 together with a handle 7 for 50 traversing the poise weight along the steelyard, and a nib 8 for locating the poise weight in the notches 9 of the steelyard 5.

The nib 8 is raised out of the notches 9 by means of the handle 10 which forms one arm of the lever 11 carrying one of the rollers, this lever being pivoted on the pin 12. The poise weight is formed with what is termed a bottom or tail section 4^a, all of the foregoing features being common to poise weight construction.

The present invention consists in the provision and disposition of the loading chamber 13 which is a separable member (see Fig. 2) disposed on the underside of the bottom or tail section of the poise weight 4^a. This loading chamber is arranged equally on either side of a vertical line which passes through the fulcrum knife edge 14 of the steelyard 5 on which the poise weight is mounted when the poise weight is in its zero position on the steelyard. The loading chamber 13 is mainly disposed within a recess 15 formed in the bottom or tail section 4^a of the poise weight and is secured in position by means of a screw 16. The loading chamber takes the form of a base plate 17 on which is formed two loading compartments 18 each of a V shape so that the molten lead 19 (or lead shot) which is placed in these compartments for the purpose of loading the poise weight 4 to its correct weight automatically positions itself within the V slots or compartments 18. The flange of the base plate 17 forms a positioning means for the loading chamber 13 relative to the underface of the poise weight as clearly seen in Fig. 3.

The particular feature of the present invention resides in the disposition of the aforesaid loading chamber 13 and in the fact that its construction is such that the balance of the steelyard 5 is not affected if any change is made in the loading thereof, with a consequent reduction of labour and saving of time when testing or rebalancing the weighing apparatus.

Claims:—

1. In a traversable poise weight for steelyards, a loading chamber disposed equally on either side of a vertical plane including the fulcrum knife of the steelyard on which the poise weight is mounted when the said poise weight is in its zero position.
2. In a traversable poise weight for steelyards,

yards, a loading chamber connected to said poise weight and disposed equally on either side of a vertical plane including the fulcrum knife-edge of the steelyard on which the poise weight is mounted when the said poise weight is in its zero position, said loading chamber being formed with a V

shaped compartment or compartments for automatically determining the position of the loading material placed therein. 10

In testimony whereof, I have signed my name to this specification.

CAMERON McGREGOR SYKES.
